UNITED STATES PATENT OFFICE.

FREDERICK CARDER, OF CORNING, NEW YORK, ASSIGNOR TO CORNING GLASS WORKS,
OF CORNING, NEW YORK, A CORPORATION OF NEW YORK.

DESIGN FOR A COMPOTE.

Application filed May 11, 1922. Serial No. 2,184. Term of patent 3½ years.

To all whom it may concern:

Be it known that I, FREDERICK CARDER, a citizen of the United States, residing at Corning, in the county of Steuben, State of New York, have invented a new, original, and ornamental Design for Compotes, of which the following is a specification, reference being had to the accompanying drawings, forming part thereof.

The figure is an elevation of a compote, showing my new design.

I claim:

The ornamental design for a compote, as shown.

FREDERICK CARDER.
